THREAD GRINDING MACHINE

Ernest A. Overstedt, Detroit, Mich., assignor to
 Louella May Dalzen, William Russel Dalzen,
 and Frederick Roy Dalzen, trustees, Dalzen
 Trust, Detroit, Mich.

Application July 23, 1945, Serial No. 606,536

27 Claims. (Cl. 51—95)

1

This invention relates to thread grinding machines and more particularly to a mechanism for rotatably and reciprocably supporting a work piece in operative relation to a rotatable thread grinding wheel.

The mechanism consists generally of a base, a base top mounted thereon, a cradle pivotally mounted on said base top, a reciprocable work piece supporting and rotating slide carried on said cradle, a wheel head housing slide on said base top in spaced relation to said cradle, and a wheel head slide vertically adjustable on said housing slide and adapted to rotatably carry a grinding wheel.

It is the object of the present invention to provide an electric power source as for instance an electric motor for delivering rotative motion through pulleys and belts to a drive shaft, which is geared to a countershaft. The latter through suitable gearing joins a third rotatable reciprocable shaft carried by the work slide. Said latter shaft delivers rotative motion to a worm shaft through suitable gears, which shaft in turn effects rotation of the work spindle carried by said slide. Said spindle is adapted for gear connection with a countershaft, which in turn meshes with a plurality of change gears for rotating a lead screw. Said lead screw engages a nut on the slide for effecting translation thereof, and the work piece supported thereby relative to a rotatable grinding wheel.

The same power source through the first mentioned drive shaft and the countershaft operated thereby actuate a cam shaft joined to said countershaft by a plurality of change gears. Said cam shaft carries a cam which is adapted to engage the under side of the cradle for effecting a relieving action thereof and its slide carried thereon relative to the grinding wheel.

It is therefore one of the objects of this invention to provide a power source which, through a plurality of gears and shafts, is adapted to effect rotation of the work spindle carried on the slide, to effect reciprocal movements of said slide, and to effect a cam actuated relieving action of the cradle and its slide relative to the thread grinding wheel.

It is the further object of this invention to provide a work slide supporting cradle with one edge thereof pivotally supported upon the base top, and with the central portion thereof supported on the base top with a cam actuated lever interposed whereby relieving action may be effected between the work piece on said slide and the grinding wheel.

2

It is the further object herein to provide means for rotating the slide supported spindle, and interconnecting means on said slide rotatably actuated by said spindle and joined to said slide for effecting longitudinal movement thereof.

It is the further object herein to provide a gear shifting means for disconnecting or interconnecting said spindle with the countershaft which operates the slide lead screw, for effecting relatively high or low speed feeding.

It is the further object of this invention to provide manual thread indexing means to rotate the lead screw effecting longitudinal adjustments of the slide and its work relative to the grinding wheel.

It is the further object herein to provide a lead screw nut consisting of two nuts one of which is bolted to a sleeve in a slide supported bracket, while the other also threaded on the lead screw is longitudinally adjustable on said sleeve for obtaining the desired fit between the lead screw nut and its lead screw.

It is the further object herein to provide manual means for raising and lowering the grinding wheel head relative to its housing, together with automatic push button controlled means for effecting a quick elevation of said head. It is the further object herein to also provide push button responsive means for quick return of said head to its initial operative position.

It is the further object herein to provide means for rotative angular adjustments of the wheel head and grinding wheel relative to its supporting slide.

It is the still further object herein to provide a cam actuated lever for supporting the machine cradle, together with means for longitudinally adjusting the fulcrum for said lever for varying the degree of relieving obtained.

It is the further object herein to provide manual means for disconnecting the lever from the machine cam to permit a fast return traverse of the grinding wheel work piece.

It is the further object herein to provide a manual slide start and stop mechanism and feed reversing means, together with means for automatically effecting said reversing.

It is the further object herein to provide a solenoid actuated ratchet mechanism to effect downward feeding of the grinding wheel head slide relative to its supporting shaft.

It is also the object to provide means for actuating said solenoid in response to push button actuation of the automatic means for elevating said supporting shaft and head carried thereby.

55 It is the further object herein to provide a

grinding wheel dresser adjustably mounted upon the grinding wheel head together with solenoid actuated ratchet means for effecting downward feeding of said dresser relative to the grinding wheel.

It is the further object to provide means for energizing the dresser feed solenoid simultaneously with the energizing of the solenoid which effects downward feed of the grinding wheel relative to the work piece. It is the further object to provide means for effecting a downward feed of the dresser relative to the grinding wheel equal to the downward feed movement of said wheel relative to said work piece, said feed distance being the amount by which the radius of the grinding wheel is reduced in the dressing operation.

It is the further object herein to provide suitable electrical connections whereby on actuation of the push button to elevate the head support, the dresser motor is energized, as well as the feed solenoid for the head, and the feed solenoid for the dresser.

It is the further object herein to provide a manual cut-out switch whereby the wheel head support may be elevated by said push button means without energizing said dresser motor or said solenoids.

These and other objects will be seen from the following specification and accompanying drawings of which:

Fig. 1 is a left side elevational view of the thread grinding machine.

Fig. 27 is an elevational view of the grinding wheel dresser and actuating motor adapted to be mounted on the wheel head.

Fig. 28 is an elevational section thereof showing the dresser feed mechanism; and

Fig. 29 is a right side elevational view thereof.

Figure 30 is a diagrammatic view illustrating the electrical circuits and the various connections between the various motors, solenoids, rheostats and switches, which form a part of the present invention.

It will be understood that the above drawings illustrate merely a preferable embodiment of the invention and that other embodiments are contemplated within the scope of the claims herein-after set out.

Referring to Fig. 14, the thread grinder comprises generally a base 11, a base top 12 thereon, a cradle 13 pivotally mounted on said base top, a slide 14 on said cradle, a grinding wheel housing slide 15 on said base top, and a wheel head slide 16 vertically adjustable upon slide 15 as shown in Fig. 1.

Base top

Referring to Figs. 14, 15, 16, 17, 18 and 13, main drive shaft 17 is rotatably mounted on base top 12 journaled within ball bearing assembly 18 at one end and with its drive pinion shaft 19, joined thereto by coupling 20, journaled within ball bearings 21. Bevel pinion 22 secured upon the end of drive shaft 19 operatively meshes with main drive bevel gear 23, which carries bushing 24 and its collar 25 keyed at 26 to work drive countershaft 27.

Countershaft 27 is journaled through bushing 28 in base top 12 on one side of gear 23 and on its other side within a needle bearing in support 29 secured to said base top. Work drive pinion 30, keyed at 31 to countershaft 27 with spacer 32 interposed, operatively meshes with intermediate idler gear 33 journaled at 34, which in turn meshes with gear 35 keyed at 36 to rotatable shaft 37.

A longitudinally slotted keyway 38, Fig. 13, is provisioned in said shaft permitting longitudinal movements thereof relative to stationary gear 35 which is retained against movement by bracket 39 and plate 40. Longitudinally movable shaft 37 is rotatably projected through bracket 39 and journaled through needle bearing 41 retained within left swivel cone 42, the latter being supported within swivel cone bushing 43 held by cradle support 44 secured to base top 12. The other end of swivel cone 42 rests upon cradle support 44.

As shown in Fig. 18, the left end of shaft 37 is retained and journaled within ball bearings 45 held by bracket 46 and cap 47 secured at the end of longitudinally reciprocal work slide 14. Drive shaft miter gear 48 is keyed at 49 to rotatable shaft 37 for effecting rotation of the work sup-

porting spindle in the manner hereafter described in detail. In Fig. 18 a corresponding swivel cone bushing 49 is provisioned within cradle support 44, for supporting right hand swivel cone 50 carrying spaced adjusting nuts 51.

Cradle

Cradle 13 shown in Figs. 13 and 18 has a pair of hollow spaced extensions 52 and 53 respectively supported and journaled upon the left and right swivel cones 42 and 50. Said cradle pivotally supported along one longitudinal edge, has a central downward projection 54 which is adapted to rest upon an active or inactive cam operative support 336 hereinafter described.

Referring to Figs. 13 and 17 work drive countershaft 27 extends outwardly through base top 12 journaled by bushing 28 and adjacent its outer end by ball bearings 55 retained by cap 56 secured to base top 12. Change gear 57 keyed and bolted to the end of shaft 27 is adapted for meshing engagement with change gear 58 keyed on the end of cam shaft 59. Change gears 57 and 58 and change gear 60 may be changed as desired for regulating the speed of rotation of cam shaft 59, as shown in Fig. 18 rotatably journaled through ball bearings 61 in base top 12 and through spaced bushings 62 and 63 carried by cradle support 44, has a cam 64 bolted at its inner end at 65.

Slide

Miter gear 48 on shaft 37 shown in Fig. 18 operatively meshes with worm shaft miter gear 67, Fig. 4, secured to worm shaft 68 by nut 69. Worm shaft 68 is angularly supported and journaled within ball bearings 70 and 71 supported by slide 14. Said slide in turn is carried by, and adapted to longitudinal reciprocal movement with respect to cradle 13 with ball bearings 72 interposed between slide ball races 73 and cradle ball races 74.

Worm shaft bearing cap 75 is suitably secured to slide 14 providing a support for lower bearing 70 as well as worm shaft 68, the latter having a squared upper end 76 for receiving a crank for manual operation if desired.

Work drive worm 77 keyed at 78 to worm shaft 68 and retained thereon by nut 79, cooperatively meshes with worm gear 80 keyed at 81 to hollow work spindle 82 shown in Figs. 3 and 4. Referring to Fig. 3, spindle 82 is rotatably journaled through bearings 83 and 84 provisioned within work slide 14, with work spindle nut 85 securing the spindle against longitudinal displacement within its slide housing.

Work spindle center 86 is retained within its adapter 87 which is secured relative to spindle drive plate 88 by nut 89. Pinion 90 and gear 91 are keyed at 92 to spindle 82 for rotation therewith, for selective meshing engagement with gear 93 or pinion 94 respectively on counter shaft 95, as shown in Fig. 5. Pinion 94 slidably keyed at 96 for longitudinal adjustment on counter shaft 95 has secured thereto gear 93 for adjustment therewith.

Countershaft 95 is rotatably journaled at its ends within bearings 97 and 98 supported within slide 14 and retained by end plate 99 and adjusting nut 100. Said countershaft extends out through end plate 101 with oil seal 102 interposed; and change gear 103 is keyed at 104 to the outer end of said shaft and is retained by nut 105. The other end of shaft 95 is enclosed within slide 14 by cover plate 106.

Transmission between spindle and lead screw

Referring to Figs. 4 and 5 gear shift finger 107 on the upper end of pivotal gear shift lever 108 extends into a corresponding annular guide opening in countershaft gear 93 whereby pivotal movements of said lever will effect longitudinal sliding translation of gear 93 and pinion 94 on countershaft 95.

Outer gear shift lever 109 is joined to inner gear shift lever 108 by interconnecting shaft 110 rotatably journaled within bushing 111 forming a part of slide 14. Plunger 112, Fig. 5, slidably retained by coil spring 113 within the upper portion of lever 109 is adapted to cooperative nesting engagement within the three gear adjustment notches 114 in slide 14. Knob 115 on the outer end of plunger 112 permits manual release thereof against the action of spring 113 and at the same time provides for manual pivotal adjustments of lever 109. With plunger 112 in the central notch, gear 93 and pinion 94 are idle with no power transmitted to lead screw actuating countershaft 95; however, with said plunger in the left hand notch 114 pinion 94 is in mesh with spindle driven gear 91 for relative high speed. On the other hand with gear shift lever 109 manually pivoted to the right and plunger 112 in the right hand notch, countershaft driving gear 93 is in meshing engagement with spindle driven pinion 90 of Fig. 3 for relative low speed.

Countershaft driven change gear 103, Fig. 5, meshes by means of intermediate change gears 103' and 116' (Fig. 2) with change gear 116, Fig. 3, keyed to hollow lead screw shaft 118 and retained thereon by collar 117 and nut 119. Shaft 118 is rotatably supported and journaled within ball bearings 120 and needle bearings 121 provisioned within slide housing 14. Lock nut 122 on shaft 118 within lead screw shaft cap 123 retains said shaft relative to ball bearings 120; while roller bearing cup 124 and ring 125 on slide 14 retain needle bearings 121.

Lead screw shaft 118 extends outwardly through oil seal 126 in slide 14 with its inner end enlarged at 127 and with an angular diverging opening for receiving the hollow interiorly threaded tapered end 128 of lead screw 129. Transverse pins 130 in shaft head 127 slidably engage the opposed longitudinal slots 131 formed in the lead screw for preventing relative rotation of shaft 118 and lead screw 129.

Draw bar 132 extends within lead screw shaft 118 with one end threadably engaging the interior threads of portion 128 of said lead screw. The other end of draw bar 132 extends out from shaft 118 and has nut 133 threaded upon the end thereof. Adjustment of draw bar 132 by nut 133 in effect draws up lead screw 129 tightly relative to its operating shaft 118 whereby rotation of said shaft effects a corresponding rotation of lead screw 129. It will be seen that said lead screw threadably extends through lead screw nuts 134 and 135 within bracket 136, Fig. 12, with its outer end journaled in bushing 137. The latter is carried by vertically adjustable support 136 resting on threaded shaft 137 journaled in tubular member 138 and retained in vertically adjusted position by nut 139. Rotation of lead screw 129 relative to its stationary nuts 134 and 135 thus effects translation of said lead screw and its slide 14 to which it is joined.

Figs. 4 and 5 show a longitudinal bar 140 secured to slide 14 by spaced studs 141. Slide dogs 75 142 and 142', Fig. 2, are adjustably carried on

bar 140 by bolts 143 for effecting reversal and direction of feed of said slide in the manner hereafter described.

Indexing means

Manual thread indexing means are employed as illustrated in Figs. 10, 11 and 12 for effecting longitudinal adjustments of the lead screw and its slide 14 relative to lead screw nuts 187 and 191 and grinding wheel 422 whereby in a thread grinding operation multiple threads may be indexed or where it is desired to pick up the lead of an existing thread, or where it is desired to grind separate nonconnecting annular threads on a work piece.

In Figs. 10 and 11 manuel lever 144 has a collar 145 at its lower end carrying a pivotal stud 146 rotatably supported within thread index bracket 147. Said bracket is in turn carried by cradle 13 by a plurality of studs 148 threaded into the longitudinally adjustable T-shaped nuts 149 slidably provisioned within corresponding T-slot 150 as shown in Figs. 11 and 12.

Cylinder 151, carried by bracket 147 and forming a part thereof, has a circular spring plate 152, Fig. 12, secured on its outer end, and a hollow reciprocal plunger 153 slidably provisioned therein. Coil spring 154 is interposed between said plunger and said plate normally maintaining its projecting end 155 within locking slot 156 formed within rotatable index disc 157.

Plunger actuating disc 158 with upwardly extending finger 159 is keyed on pivotal stud 146, with said finger extending up through a slot in cylinder 151 and into a corresponding cooperating slot 160 within the bottom of plunger 153 as shown in Fig. 10.

Pivotal movement to the left of handle 144 Figs. 10 and 12 projects plunger 153 to the left releasing index disc 157 which is now free to rotate on rotation of shaft 161 actuated by index hand wheel 162 bolted thereon at 163. Index shaft 161 with gear 164 keyed thereon is rotatably journaled and supported within bracket 147 and bracket plate 165 which is secured to bracket 147 by studs 166 for retaining engagement with annular flange 167 forming a part of shaft 161.

Gear 164 cooperatively meshes with intermediate gear 168 secured on rotatable bushing 169 carried by stud 170. The flanged portion 171 of stud 170 is secured by studs 172 to the T-nuts 149 adjustably provisioned within slot 150 in cradle 13. Gear 173 secured to rotatable bushing 169 meshes with gear 174 keyed to lead screw adjusting shaft 175 and retained thereon by spacer 176 and nut 177.

Shaft 175 rotatably journaled through collar 178, which is secured by studs 179 to cradle 13, may be locked in adjusted position by thumb screw 180 transversely extending into said collar. Lead screw adjusting shaft 175 rotatably journaled within bushing 181 in cradle 13, has keyed on its inner end a helical pinion 182 secured by nut 183 which meshes with intermediate helical gear 184 journaled on stud 185 on cradle 13.

Helical gear 186 meshes with intermediate helical gear 184 and is secured to lead screw nut 187 by studs 188, said nut threadably engaging lead screw 129 as shown in Fig. 12. Lead screw nut 187 is bolted to sleeve 189 in bracket 134 by studs 190, said bracket in turn being supported by slide 14. Lead screw nut 191 threadably engages lead screw 129 and is ex-

teriorly threaded into sleeve 189 which is retained in bracket 134 by nut 192.

Key washer 193 secured to the end of nut 192 by a plurality of studs 194, has an inwardly projecting key 195 adapted for insertion within keyway 196 in the end of sleeve 189. Said washer is adapted to retain nut 192 in any desired adjusted position relatively to lead screw 129.

Lead screw nut 191 longitudinally adjustable on lead screw 129 relative to lead screw nut 187 is locked in adjusted position by studs 197 which extend through said nut, through slots in washer 193 and into one of a plurality of slots formed in the end of sleeve 189. Thus nut 191 may be adjusted as desired relatively to nut 187 for obtaining the desired degree of fit between said lead screw nuts and said lead screw.

Grinding wheel head housing

Referring to Figs. 6 through 9, 13 and 19, wheel head slide 16 is adapted to vertical sliding adjustments within the inclined dovetail guide 200 forming a part of wheel slide housing 15. Projecting member 202 forming a part of slide 16 is secured to bracket 203 by studs 204. Wheel slide nut 205, to which is attached sleeve 206 by nuts 207, is angularly supported within said bracket and retained by collar 208 with key 209.

Wheel slide nut 205 threadably engages rotatable wheel slide screw 210, which has a central longitudinal opening 212 therein at its lower end. Head elevating shaft 213 annularly flanged at 214 has an elongated portion 215 which extends upwardly into the central opening in recessed portion 212 of screw 210 and by means of keys 216 is adapted to effect rotation of said screw, but at the same time permit independent vertical adjustment of said screw relatively thereto.

Portion 215 and key 216 are adapted for rotation while the flanged lower portion 214 of head elevating shaft 213 rests upon thrust bearings 218 which are retained by end flanges 219 secured to the hollow cylindrical portion 220 forming a part of housing 15 by studs 221.

A pair of spaced annular flanges 211 and 217 form an integral part of rotatable shaft 210, being arranged upwardly of its lower end. Said flanges provide a means for effecting upward translation of shaft 210 in the manner hereafter fully described.

Manual head elevating means

Miter gear 222 keyed on the lower end of shaft 213 meshes with miter gear 223 slidably keyed to head elevating shaft 224 but retained in engagement with miter gear 222 by bracket 225 which depends from wheel head housing 15. As illustrated in Figs. 9 and 14, said housing supported upon the thread grinding machine base top 12 is adapted to transverse adjustment on its dovetail slide connection 226 by means of manually operable screw 226', with gib 227 interposed. Said screw, supported and retained by base top 12, engages nut 227' secured to slide 15 for effecting transverse adjustments thereof. Bracket 225 carried by housing 15 maintains miter gear 223 in operative engagement with head elevating miter gear 222 in view of the slotted keyway 228 formed in shaft 224 on which gear 223 slides.

Shaft 224 is rotatably journaled at one end within a suitable bushing in bracket 29 secured by bolts 29' to base top 12 and in bushing 229 at its other end carried by member 233 forming a

part of bracket 29. Brake band bracket 231 is secured by studs 232 to member 233. Brake band 230 on bracket 231 is adjustable on the hub of gear 235 and can be locked relative thereto by adjustment of screw 234, shown in Fig. 15.

Gear 235 retained on the end of shaft 224 by nut 236 meshes with pinion 237, Fig. 13, on the end of actuating shaft 238 which is rotatably journaled at one end within a bushing in bracket 239 forming a part of support 44 on base top 12. The other end of said shaft extends through a bushing in base top 12 with collar 240 engaging the edge of said base top to prevent longitudinal movement of said shaft. The end of shaft 238 extends out through hand wheel bracket 241 on base top 12 with said bracket supporting calibrated disc 242.

Hand wheel 243 has a central supporting shaft 244 which extends into disc 242 and a plunger 245 is provisioned within said shaft with its inner square end adapted for manual sliding engagement or disengagement within a correspondingly shaped axial recess in head elevating shaft 238. Thus hand wheel 243 may be employed acting through shafts 238, 224, 213 and 210, Fig. 7, for effecting manual sliding vertical adjustments of wheel head slide 16 relatively to its housing 15.

Automatic wheel head feed

Referring to Figs. 6 through 9, ratchet feed brackets 244 and 245 bolted respectively by studs 246 on the back of wheel housing 15 carry respectively pillow blocks 247 and 248 secured thereto by studs 249. Ratchet slide bar 250 supported by the spaced pillow blocks 247 and 248 slidably carries ratchet pawl slide 251 with bushings 252 interposed as illustrated in Fig. 9. Pawls 253 pivoted on stud 254 between the side walls of pawl slide 251 are adapted to operatively engage the teeth of ratchet wheel 255. The latter, as shown in Fig. 7, is slidably keyed at 256 on sleeve 206 which is secured to nut 205 for effecting rotary movement thereof. Pawl spring 257 maintains the operative ends of pawls 253 in engagement with the teeth in ratchet wheel 255. Thus sliding movement of pawl slide 251 on shaft 250 will effect a slight rotary movement of ratchet 255 which turns slightly sleeve 206 and nut 205 secured thereto, effecting a downward feeding of the wheel slide 16, relative to screw 210.

Stud 251' extends outwardly from slide 251 in parallel alignment with shaft 250 and is engaged at its outer end by extension 258 of ratchet lever 259. Said lever is pivotally mounted on shaft 260 carried by support block 261 which is secured on slide shaft 250. Lever 259 is normally maintained inoperative or returned to its initial position by coiled spring 262 secured at 263 to said lever and at 264 to said wheel slide housing 15.

Cam disc 265 is eccentrically mounted on stud 267 within bracket 268 which is secured by studs 266 to wheel slide housing 15; and the upper end of pivotal lever 259 engages the bottom edge of said cam. Disc 265 is rotatable on stud 267 for varying the return distance of the upper end of said lever for increasing the effective action of pawl 253 relative to ratchet wheel 255. Disc 265 carries an outwardly projecting spring plunger 265' which is adapted for nesting within one of a plurality of notches 267' formed within bracket 268 for securing said disc in the desired adjusted position. Solenoid link 269 is pivotally secured to lever 259 by pin 270 and joined at its lower end to solenoid 271 by pin 272.

Energizing solenoid 271 supported on bracket

273 in housing 15, effects downward pivotal movement of lever 259, in turn causing sliding movement of pawl slide 251 on shaft 250, which results in indexing movement of ratchet wheel 255 and a predetermined downward feeding movement of wheel slide 16. For instance, it may be desirable to increase or decrease the feed movement of slide 16. This is effected by regulating the return movement of the upper end of pawl slide lever 259. Thus a greater return will result in greater feeding and a lesser return of 259 will result in a smaller feed of slide 16. The amount of return of the upper end of lever 259 is regulated by pivotal adjustment of disc 265 on its support 267. It is understood that the degree of return movement of lever 259 determines the number of teeth over which pawls 253 will pass in returning to their neutral position, corresponding to total inter-teeth distance through which ratchet wheel 255 is turned. It will be noted that slide 251 acts against return spring 251' compressing the same. On release of lever 259 said spring returns slide 251 to its initial inoperative position.

Automatic wheel head elevation

It is often desirable to quickly elevate the wheel slide 16 for inspection of the work or changing the same and for dressing the grinding wheel. To accomplish this function an electric motor 274 is employed supported within housing 15 on plate 282 adapted to effect rotary movement of shaft 275 and elevating crank 276 secured thereto. Rotatable shaft 275 is a power take-off shaft from the main drive shaft of motor 274, being operatively joined thereto in a conventional manner.

Crank 276 extends through turn buckle 277 and is pivotally secured thereto by disc 278 and stud 279. Turn buckle 280 is joined to turn buckle 277 by connecting rod 281. Stud 283 extends through turn buckle 280 and through a corresponding opening in head elevating lever 284, which has a transverse shaft 285 extending therefrom and pivotally mounted within a suitable bushing in the shoulder portion 286 forming a part of the elevating motor plate 282.

Ball bearings 287 secured on the end of head elevating lever 284 by stud 288, are adapted to be interposed between annular flanges 211 and 217 of wheel head elevating screw 210 whereby rotational movement a half turn, for instance, of crank 276 will effect a corresponding rotational movement of the turn buckle 280, which in turn effects an upward pivotal movement of lever 284 about its supporting axis 285, projecting the ball bearings 287 and shaft 210 upwardly. Means are described hereafter for limiting the pivotal movement of crank 276 to half turns at a time so that on a single energization of motor 274 from push-button 274', wheel head slide 16 is elevated; and on the next energization thereof effecting a downward pivotal movement of lever 284 the slide is returned to its initial operative position.

The pair of spaced cams 289 adjustably mounted upon and rotatably carried by crank 276, are adapted to alternately engage and operatively tilt limit switch lever 290, pivotally mounted on stud 291 and normally maintained inoperative, Fig. 7, by spring 292 on motor supporting plate 282. The other end of lever 290 normally resting on plate 282 is adapted to tilt upwardly engaging limit switch bar 293 pivoted in limit switch housing 294 at 295 to cut off the current to electric motor 274. As cam 289 sweeps

past lever 290 tilting the same to actuate limit switch 294, lever 290 is released and spring 292 returns it to the position shown in Fig. 7 ready for the next actuation by one of cams 289. The other end of limit switch actuating lever returns to rest on plate 282, also permitting limit switch bar 293 to return to its initial position as shown.

Wheel head assembly

Referring to Fig. 7, the wheel head carrying portion 417 forming an integral part of slide 16 has a longitudinal opening within which is rotatably mounted hollow drum 418 supported by adjusting ring 419. Ring 419 on slide portion 417 threadably engages said drum permitting rotational adjustment thereof.

Wheel head 420 secured to drum 418 by bolts 421 has a depending portion 421 with a transverse opening therethrough to rotatably support therein grinding wheel spindle 423 to which is secured grinding wheel 422. The lower extending portion 424 of wheel head 420 has an arcuate flange 425 thereon to which is secured arcuate segment 426 by studs 426'. Arcuate segment 428 secured to slide 16 by screws 428' has an arcuate T-slot 429 therein within which is slidably adjustable T-bolt 427 upwardly extending from segment 426. Thus the lower end 424 of head 420 is supported and locked in any desired adjusted angular position relative to slide 16. It is understood that any suitable means may be employed for obtaining rotative arcuate adjustment of wheel head 420 with respect to its supporting slide 16. Referring to Fig. 7 a gear segment 420' is secured to the under side of wheel head 420. Bracket 421' is secured to wheel head slide portion 417 and rotatably journals shaft 417' with hand wheel 417''. Worm 418' keyed to adjusting shaft 417' is angularly inclined to operatively mesh with the teeth of gear segment 420'. Thus rotation of hand wheel 417'' effects arcuate adjustment of gear segment 420' and head 420 to which it is secured.

Grinding wheel guard 429 has a bracket 430 secured thereto by bolts 431 for supporting a pair of workpiece coolant tubes 432 which are angularly inclined towards grinding wheel 422 adjacent the point of contact thereof with workpiece 433.

Upwardly extending lugs 434 form a part of drum 418 and provide a pivotal support for motor supporting plate 435 by stud 436 carried by said lugs and pivotally engaged by said plate. Motor plate 435 centrally rests upon plug 436' which is threadably and adjustably carried upon stud 437. The latter extends through cup 438 forming a part of drum 418, being bolted at 439, and up through rubber block 440 in cup 438, up through plug 436', and into a corresponding slot in motor plate 435. Nut 441 on stud 437 rests upon rubber block 440 and is adapted to provide further support for stud 437 as shown. Vertical adjustment of plug 436' is effected by rotation thereof upon its threaded supporting stud 437. It is understood that it is desirable to employ two such plugs 436' in spaced relation for supporting plate 435, with said secondary plug being adjustably supported in the manner above described. Thus a resilient seat is provided for motor 442 which is secured to plate 435 by bolts 443. Furthermore motor 442 is angularly adjustable on drum 418 for taking up the slack in drive belts 444, Fig. 6, interposed between motor pulleys 445 and the grinding wheel spindle pulleys.

Cam mechanism

Referring to Figs. 13 and 18 through 23 and particularly Figs. 20 and 19, rotatable relief cam 64 is adapted to operatively engage cam lever block 325 secured within lever 326, the latter being slidably mounted on swivel blocks 327, and the inner ends of blocks 327 are slidably positioned within longitudinal recesses in opposite sides of said lever.

The outer round ends of said swivel blocks are pivotally carried within the bifurcated portions of fulcrum 328 which is adapted to longitudinal adjustment lengthwise of said lever, and relatively to lever plate 329, along its dovetail slide connection 330. Said plate is mounted upon base top 12 and secured thereto by a plurality of studs 331.

Screw 332 rotatably journaled through bearing 333 carried by base top 12 extends into and threadably engages fulcrum 328, with collar 334 secured to said screw to retain the same against longitudinal movement. The outer end of screw 332 has an opening 335 therein for receiving a crank handle for rotating said screw, rotation of which is adapted to effect longitudinal adjustments of fulcrum 328. Operative lever block 336 engages depending member 54 of pivotal cradle 13 and, under action of rotating cam 64, alternatively raises and lowers said cradle to obtain the relieving action of the grinding wheel relative to the work piece rotatably carried by slide 14 on cradle 13.

In Figs. 19 and 20, the enlarged end of lever 326 is a pair of transverse openings 337 within which are coil springs 338 adjustably retained by plugs 338' threaded within openings 337. Springs 338 supported on base top 12 are adapted to provide a resilient support for cradle 13 which rests upon lever 326.

Cam release link 339 is loosely joined to lever 326 by stud 340 which extends through slot 341 in said link and into the end of said lever. Cam release shaft 342 rotatably extends through base top 12 with its inner end journaled through bracket 343 and keyed at 344 to crank 345, the projection 346 of which extends through a corresponding opening in cam release link 339. Bracket 343 is secured to base top 12 by studs 343'. The outer end of shaft 342 extends out through oil seal 347 and has keyed thereto at 348 bushing 349 adapted to receive and retain hand crank 350. Thus rotation of crank 350 in Fig. 20 a half turn or less causes a corresponding rotation of crank 345 and downward movement of link 339 carrying lever block 325 out of contact with cam 64. This is often desirable during a fast return traverse of the grinding wheel relative to the work piece where it is desirable to eliminate the vibration which would otherwise result.

Referring to Figs. 19, 20 and 22, it is seen that link 351 is pivotally carried on bushing 63 at one end and pivotally secured at its other end to lever 326 by stud 352, for retaining said lever against longitudinal movement relative to cam 64.

Referring to Figs. 19 through 21, relief adjusting sine bar 353 is carried by fulcrum 328 and secured thereto by studs 354. The under side of sine bar 353 is operatively engaged by stud 355 on the end of lever 356 centrally secured to rotatable shaft 357. Spring 358 anchored to base 12 at 359 is secured to the other end of lever 356 at 360, for maintaining stud 355 at all times in

engagement with the under surface of sine bar 353.

Shaft 357 rotatably journaled through the two upright members 361 and 362 forming a part of lever plate 329 is secured against longitudinal movement by collars 363. Shaft 357 extends outwardly through base top 12 as in Fig. 20 and carries at its outer end relieving index finger 364 to indicate upon a suitable index plate on base 12 the amount of relief in thousandths of an inch obtained for any particular adjustment of lever fulcrum 328.

Slide start, stop and reversing mechanism

Referring to Figs. 2 and 16, dogs 142 and 142' secured to and carried by slide 14 are on opposite sides of, and are adapted to operatively engage top limit switch lever 365 pivotally mounted on screw 366 secured to cradle 13.

The lower end 367 of lever 365 is secured to lower limit switch lever 368 by stud 369' with interconnecting link 370' and bushing 371'. Limit switch lever 368 pivotally mounted centrally to base top 12 by screw 372' is manually operated by handle 373 forming a part of lever 368 for reversing direction of movement of slide 14, or for initiating feed movement of slide 14 in one direction or the other, depending upon whether tilted to the right or left. In central position of said lever the slide is inoperative.

The lower end 374 of lever 368 has an actuating block 369 with stud 370 extending through and from opposite sides thereof, said block being adapted for reciprocal movements in recess 371 formed within base top 12. The opposite outer ends of stud 370 are adapted to separately engage either of the limit switches 372 for reversing through suitable electrical connections, the direction of feed of slide 14. This reversal may be obtained at any time by manual tilting to right or left of handle 373. On the other hand the slide will be stopped automatically by dogs 142 or 142' engaging the top lever 365 at the end of a predetermined traverse with either of said dogs projecting lever 374 to its central inoperative stopping position. To re-start in the opposite direction, it is necessary to manually project said lever handle 373 to the right or left. It will be understood also that to start feeding in one direction or the other it is necessary for said lever to be manually tilted either to the right or left of its central inoperative position, to engage either of the feed controlling limit switches 372.

Tail stock assembly

Referring to Fig. 5, the tailstock assembly 380 reciprocably mounted on slide 14 upon its dovetail portion 381 is longitudinally adjustable with respect to work spindle center 86. Referring to Fig. 24, slide 14 and dovetail 381 are shown as a right end elevational section of the tailstock assembly and slide shown in Fig. 5. Tailstock base 382 is longitudinally slidable with respect to slide dovetail 381 with gib 383 and 384 interposed.

Transverse shaft 385 rotatably journaled through tailstock base 382 threadably engages gib 383 at 386 and is adapted for operative frictional engagement with the top surface of slide 14 for locking the tailstock in any longitudinally adjusted position. Handle 387 is secured by pin 388 to the upper end of shaft 385 and is adapted to turn said shaft for locking or unlocking the tailstock in any adjusted position.

Tailstock slide 389 with dovetail slot 390 is adapted for vertical sliding adjustment relative to

dovetail 391 forming a part of tailstock base 382 as shown in Figs. 25 and 26, with gib 392 interposed. Stud 393, Fig. 24, secured to slide 389 extends therethrough and outwardly into slotted portion 394 of base 382, and is threadably engaged by screw 395. Said screw is rotatably supported in plate 395 secured by studs 397 within a corresponding recess in the top of tailstock base 382.

Opening 398, Figs. 25 and 26, in the top of screw 395 provides for insertion of manual actuating means for rotating screw 395 to effect vertical adjustments of slide 389 on base 382. Slide 389 has a longitudinal circular opening 399, Fig. 24, within which is positioned longitudinally reciprocable tailstock sleeve 400 threaded at 401 at one end and carrying work supporting center 402 at its other end.

Sleeve 400 is slidable within bushing 403 in slide 389 with seal 404 interposed between said slide and said sleeve. Coiled spring 405 within slide 389 and around sleeve 400 is retained at one end by end flange 406 secured to said slide by studs 407. The other end of said spring engages shoulder 408 forming a part of sleeve 400 normally urging the same to the right, Fig. 25, for maintaining center 402 in engagement with work piece 433 which is rotatably supported at its other end by spindle center 86.

Collar 409 is threaded onto the threaded portion 401 on the end of sleeve 400, and retained thereon by locknut 410. Actuating pins 411 extend inwardly from the bifurcated end portion 412 of tailstock handle 413 into the slots 414 in collar 409. Handle 413 pivotally mounted on hinge pin 415 extending through slide 389 is thus adapted to project sleeve 400 to the left, Fig. 25, against spring 405 for releasing the work piece. On return of handle 413 spring 405 is adapted to return sleeve 400 and its center 402 to its work holding position.

Referring to Figs. 27, 28 and 29, the grinding wheel dresser housing 446 is adapted to vertical sliding adjustment relative to vertical slide 447 with suitable ball bearings interposed. Vertical slide screw 448, Fig. 28, supported by housing 446 with bushing 449 interposed threadably engages nut 450 secured within vertical slide 447 whereby rotation of screw 448 effects vertical adjustments of housing 446 relative to said vertical slide.

Said slide is further adjustably carried by supporting bracket 451 by means of manually adjustable screw 452 rotatably carried by said bracket and threadably engaging vertical slide 447. The latter slidably engages said bracket by the dovetail connection 453.

Bracket 451 which thus adjustably carries dresser housing 446 is adapted for attachment to the grinding wheel supporting head 420, as illustrated in Fig. 7.

Thus while said bracket moves together with feed movements of the grinding wheel and head, yet vertical adjustments of the dresser housing are provided relatively to said grinding wheel to compensate for changes in wheel diameter due to wear and to dressing of the peripheral edges thereof.

Dresser housing feeding

Housing 446 is adapted to manual feeding relative to the grinding wheel by means of ratchet wheel shaft 454 rotatively mounted upon housing 446 within bushings 455 therein. Hand wheel 456 on one end of said shaft permits manual rota-

tion thereof as well as of bevel gear 451 at its other end which is in mesh with corresponding bevel gear 458 secured upon vertical slide screw 448. Thus actuating of said hand wheel effects vertical adjustments of dresser housing 446 with respect to vertical slide 447, as well as with respect to grinding wheel 422.

Housing 446 is also adapted to automatic accurate feed adjustments by means of electrically actuated solenoid 459 best shown in Figs. 28 and 29. Link 460 interconnects said solenoid and feed ratchet lever 461 by pins 462; while said lever is pivotally mounted upon ratchet wheel collar 463 forming a part of ratchet wheel 464.

The latter keyed at 465 to shaft 454 is intermittently actuated by pawl 466 in Fig. 29 pivotally carried by stud 467 extending from adjacent the end of lever 461 as shown in Fig. 27. Fig. 29 shows compression spring 468 joined to the end of pawl 466 and with its other end secured to the end of lever 461 for resiliently maintaining pawl 466 in engagement with ratchet wheel 464.

A second coil spring 469 is secured at one end at 470 to lever 461 while the other end is anchored at 471 to dresser housing 446, whereby said lever is resiliently tilted counter-clockwise. On actuation of solenoid 459 by a suitable hand switch (or by pushbutton 274' acting through suitable electrical connections) link 460 is projected downwardly effecting a clockwise pivotal movement of lever 461 and a corresponding translatory movement of pawl 466 to the right resulting in rotary movement of ratchet 464 and shaft 454.

Thus by actuation of solenoid 459 accurate and regular adjustments of the dresser housing may be effected relative to grinding wheel 422. Feed cam 473 shown in Figs. 27 and 29 adjustably supported by stud 474 on housing 446, is adapted to act as a stop for ratchet lever 461 limiting the resilient return movement counter-clockwise thereof. When set as shown in Fig. 27 cam surface 475 is engaged by said lever permitting only enough return of pawl 466 so that only one ratchet tooth is passed thereby. Consequently actuation of solenoid 459 will result in a one-half thousandths of an inch feed of dresser housing 446.

With cam 473 adjusted angularly clockwise it is seen that lever 461 can return for engagement with cam surface 476 permitting pawl 466 to pass over two teeth of ratchet wheel 464 so that upon the next actuation of said pawl the dresser housing feed will be one-thousandths of an inch.

Stop plunger 477 in Fig. 29 is resiliently urged by adjustable spring 478 into cooperative engagement with cam 473 within either opening 479 or 480, Fig. 27, for maintaining said cam in either of the two adjustments referred to.

Dresser feeding as above described may be thus effected automatically for either successive one-half thousandths of an inch feed or successive one-thousandths of an inch feed upon each actuation of solenoid 459 accompanied by downward movement of link 460. It is understood, however, that other adjustments are possible merely by changing cam 473 and its cam surfaces. The important feature herein resides in the fact that the return sweep of pawl 466 over ratchet wheel 464 is effectively regulated so that one or two teeth are encompassed by said pawl when actuated by lever 461.

Diamond dressing mechanism

For actuating the dressing mechanism a constant speed electric motor 481 is employed secured within dresser housing 446 as shown in Figs. 27

and 29. This motor is preferably a gear reduction motor with an output of two to four revolutions per minute. It is contemplated, however, that any other type of motor would also be suitable. Rotatable output shaft 482, Fig. 29, has a crank 483 thereon carrying an off-center sleeve 484, Fig. 29, upon which the upper end of connecting rod 485 is pivotally secured.

Sleeve 486 secured to pivotal operating arm 487 is pivotally joined to the lower end of connecting rod 485. Thus a single rotation of crank 483 on motor 481 effects a reciprocable arcuate movement of operating arm 487. Arcuately reciprocable arm 487 is joined to the diamond arms 15 driving disc 488.

The detail of construction of the dresser mechanism forms no part of the present invention, but is fully disclosed in co-pending application Serial No. 543,701, filed August 9, 1944, now 20 Patent No. 2,439,263, dated April 6, 1948.

Figs. 27, 29 and 28 illustrate the dresser mechanism as forming a part of the thread grinding machine, being an element thereof; and the above description illustrates its mode of support upon the grinding wheel head, and the method of feeding the dresser relative to its supporting wheel head.

Solenoid 459 is employed to effect feeding of dresser housing 446, and is actuated either by a 30 separate switch or automatically through suitable electrical connection by pushbutton 274'. Said pushbutton is also connected with dresser motor 481 for energizing the same to effect the dressing operation on grinding wheel 422, at the same time as the head slide 16 is elevated by said pushbutton in the manner fully described above. It will be noted that said dresser motor may be disconnected by a suitable switch from said pushbutton so that there will be no dressing operation upon actuation of said pushbutton.

It will be noted also that the electrical connections to the pushbutton 274' are such that both solenoids 459, Fig. 29, and 271, Fig. 6, are simultaneously energized. Solenoid 271 effects a 45 downward feed, through ratchet 255, of the grinding wheel relative to the work piece, a predetermined distance which is equal to the reduction of radius of said wheel effected by the dressing operation. At the same time solenoid 459 through ratchet 464 effects a feed of the dresser housing 50 relative to the grinding wheel, which feed is likewise equal in distance to the reduction of radius of said wheel effected during the dressing operation.

Operation

Referring to Fig. 2, pushbutton 274' is employed for energizing motor 274, Fig. 7, through suitable electrical connections to effect automatic and quick elevation of the wheel head slide 16 and its supporting screw, carrying grinding wheel 422, in the manner above fully described. Pushing button 274' a second time effects a quick downward return of said grinding wheel into operative engagement with rotatable work piece 433 shown in dotted lines in Fig. 7.

Through other electrical connections said pushbutton is joined to a grinding wheel dresser motor to effect dressing of wheel 422 at the same time as the wheel head slide is elevated.

Also said pushbutton is joined by suitable electrical connections to solenoid 271 to effect a predetermined downward feed of the wheel head and grinding wheel slide relative to its supporting screw. Said downward feed movement is equal

to the reduction of radius effected by the wheel dresser, and thus provides an automatic compensation for said reduction of the wheel radius, and guarantees that said wheel will be returned to its proper operative position relative to work piece 433 upon the second actuation of pushbutton 274'.

Control panel 446', Fig. 2, on the front of the thread grinder, has a motor starting pushbutton 447' and stopping button 448' with suitable electrical connections provided therefor, to effect starting and stopping of work rotating spindle 86 on slide 14, Fig. 5. With hand lever 373, Fig. 2, in its central position, neither limit switch 372 is energized. Therefore it is necessary to throw lever 373 to the right or left for determining the direction of rotation of spindle 86.

It will be noted also that there can be no movement of slide 14 with manual plunger 115, Figs. 2 and 5, in its central position in notch 114, inasmuch as gears 93 and 94 on countershaft 95 are out of mesh with gears 90 and 91 on spindle 82.

Thus lever 109 with handle 115 must also be tilted either to the right or left for relatively high or low speed of countershaft 95 through cradle gears 91 and 94 or gears 90 and 93.

With lever 109 tilted to either left or right, slide 14 will also be actuated when pushbutton 447' is actuated.

Rotatable speed control rheostat 449' on panel 446' regulates the speed of rotation of work spindle 86 as well as the movement of slide 14. Rheostat 450' regulates the speed when the spindle and slide are operating in reverse.

Pushbutton 451' energizes and button 452' de-energizes motor 442 which controls rotation of grinding wheel 422 through pulleys 444, so that said grinding wheel may be started and stopped at will.

Solenoid switch 453' turns either to the "on" or "off" position for cutting in or out solenoid 271 which in the "on" position will be energized to effect downward feed of wheel head 420 on slide 16 when pushbutton 274' is actuated to elevate slide 16.

Dresser switch 454' through suitable electrical connections is adapted to energize the dresser motor independently of pushbutton 274'. The latter automatically energizes the dresser at the same time as motor 274 is energized to elevate wheel head slide 16.

Switch 455' turns either to the "on" or "off" position for starting or stopping the work coolant motor 456' shown in Fig. 1 and connected with coolant tank 457'.

Pushbutton 458' is a master stop for all motors, i. e. work slide motor, grinding wheel motor 442, coolant motor 456', as well as head elevating motor 274, solenoid 271, dresser motors, etc.

It will be noted that work spindle and slide actuating motor as well as grinding wheel motor 442 are direct current motors adapted to deliver a constant torque regardless of load and at the same time very susceptible to variable speed adjustment through rheostat switches 449' and 450'. Heretofore variable speeds were attained by step pulleys and four speed alternating current motors neither of which proved satisfactory, and particularly because of the speed variation often resulting from variations in the load.

To overcome this difficulty the inventor employs said direct current motors using an alternating current rectifier mechanism for converting the conventional alternating current to di-

rect current. While the detail and construction of the rectifier are not material to or a part of the present invention, the entire rectifier unit as a whole is considered an essential element in the combination permitting the use of direct current motors in the operation of the thread grinding machine.

Having described my invention, reference should now be had to the claims which follow for determining the scope thereof.

I claim:

1. A thread grinding machine comprised of a base, a cradle pivotally mounted on said base, a longitudinally reciprocal work slide carried by said cradle, a longitudinally adjustable wheel head slide on said base spaced from said cradle and having an inclined guide means, a grinding wheel head adapted for reciprocal vertical sliding movements on said means, a grinding wheel dresser adjustably mounted on said wheel head, a pushbutton, pushbutton responsive means for elevating said head, and electrical means interconnecting said pushbutton and dresser for energizing said dresser simultaneously with the elevation of said head.
2. In a thread grinding machine, a wheel head housing slide, a grinding wheel head with a supporting slide vertically adjustable thereon, a pushbutton, pushbutton responsive means joined to said head slide for elevating said head, operative means joined to said head slide for effecting a downward feed of said head relative to said housing slide, a grinding wheel dresser adjustably mounted on said wheel head, and electrical means interconnecting said pushbutton and dresser, and said pushbutton and said head feeding means, for energizing said dresser and said feeding means simultaneously with pushbutton elevation of said head.
3. In a thread grinding machine, a wheel head housing slide, a grinding wheel head with a supporting slide vertically adjustable thereon, a pushbutton, pushbutton responsive means joined to said head slide for elevating said head, operative means joined to said head slide for effecting a downward feed of said head relative to said housing slide, a grinding wheel dresser adjustably mounted on said wheel head, operative means joined to said dresser for effecting a downward feed of said dresser relative to said head, and electrical means interconnecting said pushbutton and dresser, said pushbutton and said head feeding means, and said pushbutton and said dresser feeding means, for energizing said dresser and said head and dresser feeding means simultaneously with pushbutton elevation of said head.
4. In a thread grinding machine, a wheel head housing slide, a grinding wheel head with a supporting slide vertically adjustable thereon, a motor joined to said head slide for elevating said head, a head feeding solenoid, solenoid operative means joining said head slide for effecting a downward feed of said head relative to said housing slide, a grinding wheel dresser adjustably mounted on said head, a motor for activating said dresser, a dresser feeding solenoid, solenoid operative means joined to said dresser for effecting a downward feed of said dresser relative to said head, a pushbutton, and electrical means connecting said pushbutton with said head elevating motor, with said head feeding solenoid, with said dresser motor, and with said dresser feeding solenoid for simultaneous operations thereof on actuation of said pushbutton.
5. In a thread grinding machine, a wheel head

housing, reciprocal screw means thereon, a grinding wheel head, threaded means thereon vertically adjustable on said screw means, a motor joined to said screw means for elevating the same and the head thereon, a head feeding solenoid, a solenoid actuated ratchet on said threaded means for rotating the same for effecting a predetermined downward feed of said head relative to said screw means, a grinding wheel dresser adjustably mounted on said head, a motor for actuating said dresser relative to the grinding wheel effecting a reduction in radius thereof equal to said predetermined distance, a dresser feeding solenoid, a solenoid actuated ratchet joined to said dresser for effecting a downward feed thereof of the same predetermined distance relative to said grinding wheel, a pushbutton, and electrical means interconnecting said pushbutton with said screw elevating motor, with said head feeding solenoid, with said dresser motor, and with said dresser feeding solenoid for simultaneous operations thereof.

6. A thread grinding machine comprised of a base, a rotatable power source including a drive shaft journaled thereon, a cradle pivotally mounted on said base, a work spindle carrying slide reciprocally mounted on said cradle, a lead screw rotatably carried by said slide and engageable with a stationary nut on said base, a rotatable cam shaft joined to said drive shaft, journaled within said base and carrying a cam adapted for operative engagement with said cradle, a reciprocal rotatable spindle drive shaft also joined to said first drive shaft, an inclined shaft carried by said slide operatively connected to said spindle drive shaft, a rotatable spindle on said slide operatively connected to said inclined shaft, and operative interconnecting means intermediate said spindle and said lead screw for effecting longitudinal movements of said slide relatively to said base.

7. In a thread grinding machine, a base, a rotatable power source including a drive shaft journaled therein, a work spindle carrying slide reciprocally mounted on said base, a spindle drive shaft journaled within said slide and adapted to reciprocal movement therewith, intermeshing means intermediate to said drive shaft and said spindle drive shaft, a miter gear on said latter shaft, a work spindle rotatably mounted on said slide and carrying a worm gear, and an inclined worm shaft carried by said slide with a miter gear on one end meshed with said first miter gear, and with a worm adjacent its other end meshed with said spindle worm gear.

8. In a thread grinding machine, a base, a reciprocal slide thereon, a rotatable work spindle on said slide, a rotatable lead screw on said slide adapted for engagement with a stationary nut on said base, a rotatable countershaft journaled on said slide and joined to said spindle, a hollow lead screw shaft journaled on said slide and operatively joined to said countershaft, and locking means extending through said lead screw shaft for operative engagement with said lead screw for tightly drawing up the latter with respect to said shaft for rotation therewith.

9. In a thread grinding machine, a base, spaced swivel means carried on said base, a cradle with spaced projecting means pivotally mounted on said swivel means, a lever pivotally mounted on said base and engageable near one end with said cradle, a rotatable cam shaft journaled on said base carrying a cam engageable with the other end of said lever for effecting intermittent verti-

cal displacements of said cradle, a power source including a drive shaft journaled in said base, a countershaft on said base interconnected with said drive shaft and said cam shaft, a spindle carrying reciprocal slide on said cradle, a rotatable spindle actuating drive shaft on said slide slidably positioned through one of said swivel means and operatively joined with said countershaft.

10. In a thread grinding machine, a base, a slide supporting cradle pivotally mounted thereon, a rotatable cam shaft on said base carrying a cam, a lever pivotally mounted on said base with one end engaging said cam and with its other end engaging the under surface of said cradle for effecting vertical intermittent displacements thereof around its pivotal support, and resilient means interposed between said lever and said base adjacent the cradle engaging end of said lever for taking up the greater portion of the weight of said cradle.

11. In a thread grinding machine, a base, a slide supporting cradle pivotally mounted thereon, a rotatable cam shaft on said base carrying a cam, a lever pivotally mounted on said base with one end engaging the under surface of said cam and with its other end engaging the under surface of said cradle for effecting vertical intermittent displacements thereof around its pivotal support, and a manually rotatable shaft loosely joined to the cam end of said lever for tilting the same downwardly and retaining the same out of operative engagement with said cam.

12. In a thread grinding machine, a base, a slide supporting cradle pivotally mounted thereon, a rotatable cam shaft on said base carrying a cam, a longitudinally adjustable bifurcated fulcrum on said base, a pair of swivel blocks pivotally carried thereby and extending inwardly, and a lever longitudinally slotted on opposite sides for slidably receiving said swivel blocks, with one end of said lever engaging said cam and with its other end engaging the under surface of said cradle for effecting vertical intermittent displacements thereof around its pivotal support.

13. In a thread grinding machine, a base, a slide supporting cradle pivotally mounted thereon, a rotatable cam shaft on said base carrying a cam, a fulcrum longitudinally adjustable on said base, a lever pivotally mounted thereon, with one end of said lever engaging said cam and with its other end engaging the under surface of said cradle for effecting vertical intermittent displacements thereof around its pivotal support, a sine bar carried by said fulcrum, and a shaft journaled on said base carrying an indicating finger rotatably responsive to the surface of said sine bar on adjustments of said fulcrum, to indicate the degree of lever actuated cradle displacement corresponding to a particular longitudinal adjustment of said fulcrum.

14. In a thread grinding machine, a base, a longitudinally reciprocal slide on said base, a hollow bracket on said base, a nut carried in said bracket, a rotatable lead screw carried by said slide and threaded through said nut for effecting longitudinal movements of said lead screw on rotation thereof, a gear on said nut, manually rotatable gear means joined to said nut gear for rotating the same in its bracket to effect indexing longitudinal movements of said lead screw and its supporting slide, a resilient plunger on said base normally locking said manually rotatable gear means, and pivotal means engageable with

said plunger for displacing the same to release said gear means.

15. In a thread grinding machine, a base, a wheel slide housing thereon having an inclined slide, a wheel head slidably positioned on said slide for vertical adjustments thereon, threaded means rotatably mounted on said housing, means carried by said wheel head threadably engaging said threaded means, for effecting vertical movements of said head on rotation of said threaded means, manually rotatable means journaled through said base operatively engaging said threaded means for effecting rotation thereof, and adjustable brake band means engageable with said manually rotatable means for locking said head in any vertically adjusted position.

16. In a thread grinding machine, a base, a wheel slide housing longitudinally adjustable thereon having an inclined slide, a wheel head slidably positioned on said slide for vertical adjustments thereon, threaded means rotatably mounted on said housing, means carried by said wheel head threadably engaging said threaded means for effecting vertical movements of said head on rotation of said threaded means, gear means on the lower end of said threaded means, manually rotatable means journaled within said base, and second gear means depending from said housing operatively engaging said gear means and slidably keyed to said rotatable means.

17. In a thread grinding machine having a work piece supporting spindle, a base, a wheel slide housing thereon having an inclined slide, a wheel head slidably positioned on said slide for vertical adjustments thereon, threaded means rotatably supported on said housing, means carried by said wheel head threadably engaging said threaded means, for effecting vertical movements of said head on rotation of said threaded means, and pivotal means joined to said threaded means for mechanically lifting said threaded means upwardly relatively to said housing carrying said head away from said spindle.

18. In a thread grinding machine having a work piece supporting spindle, a base, a wheel slide housing thereon having a slide, a wheel head slidably positioned on said slide for vertical adjustments thereon, threaded means rotatably supported on said housing, means carried by said wheel head threadably engaging said threaded means, for effecting vertical movements of said head on rotation of said threaded means, and pivotal means joined to said threaded means for mechanically lifting and dropping said threaded means upwardly and downwardly relatively to said housing carrying said head away from said spindle.

19. In a thread grinding machine having a reciprocal work supporting carriage, a base, a wheel slide housing thereon having a slide, a wheel head slidably positioned on said slide for vertical adjustments thereon, threaded means rotatably mounted on said housing, means carried by said wheel head threadably engaging said threaded means, for effecting vertical movements of said head on rotation of said threaded means, pivotal means on said housing joined to said threaded means for lifting the same upwardly independently of the movement of said carriage, and a motor driven rotatable crank joined to said pivotal means.

20. In a thread grinding machine, a base, a wheel slide housing thereon having a slide, a wheel head slidably positioned on said slide for

vertical adjustments thereon, threaded means rotatably mounted on said housing, means carried by said wheel head threadably engaging said threaded means, for effecting vertical movements of said head on rotation of said threaded means,

5 pivotal means on said housing joined to said threaded means for projecting the same upwardly, a motor driven rotatable crank joined to said pivotal means, a push button, and a crank driving motor connected thereto, and adapted for intermittent pushbutton responsive half turns for alternately raising and lowering said head.

15 21. In a thread grinding machine, a base, a wheel slide housing thereon having a slide, a wheel head slidably positioned on said slide for vertical adjustments thereon, pivotal means on said housing joined to said head for projecting the same upwardly, a motor, and a motor driven rotatable crank joined to said pivotal means.

20 22. In a thread grinding machine, a base, a wheel slide housing thereon having a slide, a wheel head slidably positioned on said slide for vertical adjustments thereon, pivotal means on said housing engageable with said head for projecting the same upwardly, a motor, a push button connected therewith, and a motor driven rotatable crank joined to said pivotal means for intermittent pushbutton responsive half turns for alternately raising and lowering said head.

25 30 23. In a thread grinding machine, a base, a wheel slide housing thereon having a slide, a wheel head slidably positioned on said slide for vertical adjustments thereon, threaded means mounted on said housing, rotatable means carried by said wheel head threadably engaging said threaded means, for effecting vertical movements of said head, rotatable ratchet means slidably keyed to said rotatable means for effecting intermittent predetermined rotation of the rotatable means, a push button, and a pushbutton responsive solenoid joined to said ratchet means for effecting intermittent feed movements thereof.

40 35 24. In a thread grinding machine, a base, a wheel slide housing thereon having a slide, a wheel head slidably positioned on said slide for vertical adjustments thereon, threaded means mounted on said housing, rotatable means carried by said wheel head threadably engaging said threaded means for effecting vertical movements of said head, a ratchet wheel slidably keyed to said rotatable means, pawl carrying means slidably mounted on said housing to intermittently rotate said ratchet wheel for effecting predetermined rotation of the rotatable means, a push button, 45 and a push button responsive solenoid operatively engageable with said pawl carrying means.

50 55 25. In a thread grinding machine, a base, a wheel slide housing thereon having a slide, a wheel head slidably positioned on said slide for vertical adjustments thereon, threaded means having a central opening at its lower end rotatably and reciprocally mounted on said housing, rotatable means carried by said wheel head threadably engaging said threaded means for effecting vertical movements of said head on relative rotation of said threaded means, manually rotatable means on said housing slidably keyed up into the opening in said threaded means adapted to effect rotation thereof without interfering with its reciprocal vertical movements, and rotatable ratchet means on said rotatable means for effecting intermittent predetermined rotative movements thereof.

60 65 70 75 26. In a thread grinding machine, a base, a wheel slide housing thereon having a slide, a

wheel head slidably positioned on said slide for vertical adjustments thereon, threaded means rotatably and reciprocally mounted on said housing, rotatable means carried by said wheel head threadably engaging said threaded means for effecting vertical movements of said head on relative rotation of said threaded means, manually rotatable means on said housing slidably keyed to said threaded means adapted to effect rotation thereof without interfering with its reciprocal vertical movements, rotatable ratchet means on said rotatable means for effecting intermittent predetermined rotative movements thereof, and movable means engageable with said threaded means for mechanically projecting said threaded means upwardly relatively to its supporting housing carrying said head therewith.

27. In a thread grinding machine, a base, a longitudinally reciprocal slide on said base, a power source for effecting movements of said slide spaced slide dogs extending from said slide, a limit switch lever pivotally mounted on said base and alternately engageable at its upper end by said dogs to de-energize a limit switch, a manual limit switch lever pivotally mounted on said base with the lower end of said first limit switch lever pivotally joined thereto, and spaced direction controlling limit switches connected to said

10
